CLAIM

The ornamental design for a cable connector, substantially as shown and described.

DESCRIPTION

FIG. 1 is a perspective view of the cable connector showing our new design with the end cap shown in the closed position;

FIG. 2 is a side elevational view thereof;

FIG. 3 is a top plan view thereof;

FIG. 4 is an opposite side elevational view thereof;

FIG. 5 is a bottom plan view thereof;

FIG. 6 is an end elevational view thereof;

FIG. 7 is an opposite end elevational view thereof;

FIG. 8 is a slightly enlarged perspective view thereof with the end cap shown in the open position.

The electric cord is shown broken away to depict indeterminate length.
